DESK TRAY OR SIMILAR ARTICLE

William E. L. Bunn, Fort Madison, Iowa, and James V. Vevirit, Kenmore, N.Y., assignors to W. A. Sheaffer Pen Company, Fort Madison, Iowa, a corporation of Delaware

Filed Nov. 13, 1963, Ser. No. 77,405

Term of patent 14 years

(Cl. D74—9)

FIG. 1

We claim:

The ornamental design for a desk tray or similar article, as shown.
